UNITED STATES PATENT OFFICE.

ADOLF GLASER, OF NEW YORK, N. Y.

SEPARABLE BUTTON.

Application filed May 26, 1923. Serial No. 641,791.

To all whom it may concern:

Be it known that ADOLF GLASER, citizen of Roumania (having declared his intention of becoming a citizen of the United States), residing at 115 East 92nd Street, city of New York, State of New York, % Wohlman, has invented new and useful Improvements in Separable Buttons, of which the following is a specification.

10 My invention relates to improvements in separable buttons, such as, for example, cuff buttons for soft cuffs; ear-rings and buttons adapted to be attached to garments without the use of thread or like fastening means.

15 The object of my invention is to provide a separable button of this character which has the facility for being quickly separated when a cuff is to be removed, and which 20 when separated the two sections will remain in the button holes of the cuffs, and which further may be readily removed and inserted in the cuffs. I accomplish this object by means of the device hereinafter fully described and illustrated in the accompanying drawing, in which, Figure 1 is a perspective of the two parts of my improved button shown in separated position; Figure 2 is a longitudinal sectional view taken 25 through the button and showing the parts thereof in engaged position; Figure 3 is a transverse sectional view taken on the line 3—3 of Figure 2; Figure 4 is a perspective view of my invention applied to an ear-ring; Figure 5 is a cross sectional view through the head of the female part of the button showing a locking means; Figure 6 is a cross sectional view on the line 6—6 of Figure 7 which shows a locking means 30 for holding the parts of the button from becoming separated; Figure 8 is a further modification of the holding means; and Figure 9 is a still further modification of holding means when one part 35 is provided with a sharp point; and Figure 10 is a modification of the invention showing the fastening means separable from the main portions of the button.

40 Referring to the drawings and particularly to Figures 1, 2, and 3, 10 denotes a button comprising two separable parts 11 and 12, and part 11 being the male portion and the part 12 being the female portion. As shown in Figures 1 and 2 the male part 45 11 comprises a head portion 13 having an integral shank 14 projecting axially there-

of. The free end of the shank is provided with an annular groove 15 and a projecting locking pin 16. The pin 16 extends axially of the shank 14 and the end is bent 60 at right angles, as indicated at 17. The female part 12 is similar in shape to the part 11 except that instead of the pin 16 the shank 14^a is provided throughout its length with a bore 18 and radial slot 19 to 65 receive the pin 16. The head portion 13^a of the part 12 is preferably hollow and the inside wall of the head is provided with a radial slot 20 forming a continuation of the slot 19 at the point where the shank 70 and the inside wall of the head are joined together.

In the application of the buttons to a cuff, the shanks 14 and 14^a are inserted through the button holes and a washer 21 75 is inserted in each of the grooves 15, the washers 21 being disposed on the inside of the cuffs. The washers 21 comprise flat disk members provided with a central opening 22 and radial slot 23, as shown in Figure 80 3; the space between the walls of the opening 22 being of a dimension to closely embrace the bottom of the groove 15 and the wall of the radial slot 23 being substantially smaller than the diameter of the 85 opening 21. This construction is provided so as to prevent the washer from becoming disengaged from the shank and in order to enable the washer to be received by the groove 15 the material at one side of the 90 opening 22 and slot 23 is provided with a slit 24, which closes when the washer is being placed in position.

In Figure 4, the pin 14^a projects from a mounting 25 which carries a stone 26 and 95 which may be worn as an ear-ring or stud. The locking portion or back member comprises a shell 27 having a radial slot 28 to receive the bent portion 17^a of the pin.

Figure 5 shows a means for holding the 100 bent portion 17 of the pin 16 from becoming disengaged from the head portion 13^a. The means comprises spring 29 secured at one end to the inside periphery of the head 13^a and having its other end bent so as to 105 operate substantially parallel with the wall of the slot 20, the end of the spring being provided with a beveled toe 30 which has a straight surface disposed towards the center of the head and on a plane adapted to 110 engage the wall of the pin 16 when the latter is disposed in the head as shown in

Figure 5. The other edge of the toe 30 is inclined so that when the bent portion 17 is inserted into the slot the pin will merely cause the spring to move the toe 5 out of the path of incoming pin. When the pin is finally engaged the toe 30 moves to its initial position over the slot and the pin is prevented from riding out of the said slot, however, if it is desired to remove the 10 pin 16 the latter may simply be moved with sufficient force to cause the bent portion 17 to push the toe 30 out of the path of the portion 17 through the slot 20.

The means for holding the pin 16 in the 15 head 13^a, as shown in Figures 6 and 7, comprises a spring tongue 31 projecting from one edge of the slot 20 closely adjacent the center portion of the slot. The tongue is adapted to overlie the slot and to project 20 transversely thereof. The free end of the tongue projects to a plane substantially above the center of the pin, as shown in Figure 6, a construction which enables the pin to be inserted into the head through 25 the slot 20. During the movement of the pin 16 through the slot 20 the tongue is pushed upwardly and a short rotation of the pin will cause the bent portion to ride out from under the tongue whereupon the latter 30 will spring back to its initial position. To remove the pin the bent portion 17 is rotated until it engages under the lip of the tongue 31 which will be forced upwardly and allows the portion 17 to register with 35 aid and be withdrawn through the slot 20.

In Figure 8, the pin 16 is adapted to project to a point short of the inner periphery of the hollow head 13^a which is provided with a curved wire locking member having 40 a notch or upright groove 32 to receive the blunt end of the bent portion 17 of the pin 16. On the other hand if the bent portion 17 is provided with a pointed end 17^b the pin may be yieldably held by a tongue 33 cut 45 in the inside wall or face of the head portion 13^a, as shown in Figure 9. The tongue in this case is disposed on a curve concentric with the periphery of the head and at the mid-portion thereof the tongue is provided 50 with a radially arranged groove 34 to receive the bent portion 17 of the pin, as shown in Figure 9.

Referring to Figure 10, the two parts of the button are exactly alike and consist of 55 a flat head portion 35, and shank 36, the latter being provided with an annular groove 37 adjacent the end. In this form of the invention the parts are connected or 60 separably attached together by means of washers 38 and 39, which consist of flat plates having central openings 40 and outwardly disposed slots 41, the latter being adapted to slide over the grooved channel 37 in the shank 36, and the walls of the 65 opening 41 being of a size to very closely

embrace the bottom of the said groove. In order to permit the washers 38 and 39 to be slipped over the shanks the former are provided with slits cut in the metal around one side of the slot 41 and opening 40 in the 70 manner similar to the one employed in connection with the washers shown in Figure 1. The washer 38 is provided with oppositely disposed lugs 42 or hooks, or other similar fastening means, one being disposed on each 75 side of the opening 40. The other washer 39 is provided with a transversely disposed loop 43 and hook 44 both of which are adapted to receive the hooks 42 of the first 80 washer 38. To attach the parts of the button together the washers are placed in position after the shanks 36 have been inserted in the cuffs and then one hook 42 of the washer 38 is engaged in the loop 43 of the washer 39 and the other hook 42 is engaged under the hook 44 by moving one part 85 slightly at an angle with respect to the other part of the button, or where different closures are used, they are brought similarly 90 together.

The operation involved in attaching the two parts of the button together to hold a cuff in proper position is very simply carried out and consists in placing the shanks through the button holes in the cuffs so that the head portions are disposed on the outside and the two shanks are directed toward each other. The washers are then slipped into the grooves in the shanks and against 95 the inner side of the cuffs. In the design shown in Figure 1, the bent portion of the pin is inserted in the slot of the other part of the button and then the part having the pin is rotated slightly whereupon the said 100 bent portion of the pin will be engaged by a holding means such as one of those described and illustrated in Figures 5, 6, and 9.

Throughout the several views it will be noted that where the free end 17, 17^a and 17^b of the pins 16 and 16^a are shown as being blunt, the head of the slot 20 is preferably of a slightly increased diameter so as to receive the stem portion 16 of the pin, the stem in this form being slightly greater in 110 diameter than the bent portion or end 17. On the other hand, in the modifications 115 showing the pin as being pointed, the slot 20 is uniform throughout its length.

Referring to the ear-ring, the pin portion is inserted in the wearer's ear and the disk 120 portion having the radial slot is placed over the bent end portion of the pin and rotated slightly. Any of the holding means for the pin may be used in the construction of the ear-ring disk piece.

Having described my invention what I 125 claim and desire to secure by Letters Patent is:

1. A separable button including two members having shanks, one shank having the 130

end thereof bent at an angle to form an L-shaped portion and the other shank being provided with a radial slot opening to receive said L-shaped end portion, and a yieldable holding means disposed in the member having the slotted shank to engage the bent end of the other member when the latter is rotated with respect to the first member.

2. A separable button as claimed in claim 10 1, in which the said shanks are provided with annular grooves, adjacent their free ends, and radially slotted washers insertable in said grooves to form channels for the material holding the said button, substantially as described.

3. A separable button as claimed in claim 1, in which the said shanks are provided with annular grooves adjacent their free ends, and slotted washers insertable in said 20 grooves to form channels for the material holding said button, said washers being provided with slits to enable the walls of the slots to receive the said grooves, substantially as described.

4. A separable button, as claimed in claim 1, in which said holding means comprise a member having a recess to embrace the said bent end of the L-shaped portion of the shank, substantially as described.

5. A separable button, as claimed in claim 1, in which said holding means is mounted in the hollow head portion of said button and comprises a tongue disposed in the path of movement of said bent end portion of the L-shaped projection of said shank, said tongue having a groove adapted to embrace the bent end portion when the latter is moved to register therewith, substantially as described.

6. A separable button for an ear ornament

comprising a head member provided with an axially projecting L-shaped stem bent at its free end and reduced in diameter, a flat, hollow, interlocking member, having a radial key slot, and means disposed within the 45 hollow member to yieldably engage the said bent portion of the stem to hold the latter against movement within the member.

7. A separable button, comprising a head member provided with a projecting L-shaped 50 pin, a second head member provided with a slot to receive the end portion of the L-shaped pin, and a spring locking arrangement having a beveled toe overlying the said slot adjacent the inner end thereof; said toe 55 being capable of holding the said pin against the end wall of the slot and to prevent the bent end portion from disengaging itself from the first head member.

8. A separable button, as claimed in claim 1, in which the said pin is blunt at its free 60 end and the holding means comprise a serpentine spring portion disposed in the head of the button adjacent the wall thereof, whereby the rotary movement of the end of 65 the L-shaped portion of the pin will engage between the curves of the said spring portion, substantially as described.

9. A separable button as claimed in claim 1, in which the end of the L-shaped portion 70 of the pin is provided with a point and the yieldable holding means comprises a flat spring portion having a curved groove into which the bent portion of the pin adjacent the end thereof is adapted to be held, substantially as described.

In testimony whereof, ADOLF GLASER has signed his name to this specification, this 15th day of May 1923.

ADOLF GLASER.
